UNITED STATES PATENT OFFICE.

JESSE E. MILLER, OF KNOXVILLE, TENNESSEE.

BAG-CLOSING MACHINE.

1,321,232.

Specification of Letters Patent.

Patented Nov. 11, 1919.

Application filed March 5, 1918. Serial No. 220,607.

To all whom it may concern:

Be it known that I, JESSE E. MILLER, a citizen of the United States, residing at Knoxville, in the county of Knox and State of Tennessee, have invented a new and useful Improvement in Bag-Closing Machines, of which the following is a specification, reference being had to the accompanying drawing.

10 My improvement relates particularly to sewing machines for closing filled bags, such bags being closed by sewing across the upper end instead of tying such end. But my improvement is applicable also to sewing machines for sewing other articles which are delivered successively to the sewing mechanism.

For examples of such machines, reference is made to my Letters Patent of the United 20 States, No. 924,175, granted June 8, 1909; and No. 918,184, granted April 18, 1909; and No. 973,123, granted October 18, 1910.

The object of the present improvement is to embody in such machines better means 25 for conveying the bags to and beyond the sewing mechanism.

Generally speaking, the improvement consists in a main conveyer section placed under the sewing head, and associated therewith 30 means for moving said main section upward and downward, and an auxiliary conveyer section associated with said main section, the auxiliary section being placed in approximate alinement with the main section and having one end meet one end of the main 35 section and said end of the auxiliary section being arranged to move up and down independently of its other end and to conform with the up and down movements of the 40 main section.

Two forms of the improvement are described herein and illustrated in the accompanying drawings. In the first of these forms one end of the main section of the conveyer is relatively distant from the sewing head while the other end extends beneath the sewing head, the distant end being hinged to a fixed support, and the other end being movable up and down. From the hinged end of 45 the main section, a stationary conveyer section extends still farther from the sewing head. A single conveyer belt extends around both of these sections. Filled bags are placed upon this belt and brought to the

sewing head. At the movable end of the 55 main section is an auxiliary conveyer section in approximate alinement with the main section and having the end adjacent the main section arranged for up and down movement synchronously with the up and down movements of the main section, while the opposite end of the auxiliary section is stationary or approximately stationary. The auxiliary section has a conveyer belt independent of the belt of the main conveyer. The function 60 of this auxiliary conveyer is to receive bags from the main conveyer and convey them to a chosen discharge point. This auxiliary conveyer may be of such length as will meet the requirements of any given case. In the 65 second of these forms, the main conveyer section has a parallel or bodily up and down movement under the sewing head, and at each end of the main section is an auxiliary conveyer section arranged in approximate 70 alinement with the main section and having the ends adjacent the main section movable up and down synchronously with the up and down movements of the main section. A belt surrounds the main and the auxiliary 75 section over which bags travel toward the sewing head. The other auxiliary conveyer section has its own conveyer belt.

In both of these forms, the belt which is applied to the main conveyer section may 80 also be applied to the auxiliary conveyer section over which the bags are conveyed from the main conveyer section; but this is not necessary, because the bags leaving the main conveyer section may be allowed to fall forward lengthwise and land upon the auxiliary 85 conveyer belt, if they do not pass the gap between the two belts without falling.

In both of these forms, in the particular embodiment shown by the drawings, the ends 90 of the auxiliary conveyer sections which meet the main conveyer section are so coupled or articulated to the main section as to cause the adjacent ends of the auxiliary sections to be supported and moved up and 95 down by the main section.

In the accompanying drawings,

Figure 1 is a plan of an apparatus embodying the first of said forms:

Fig. 2 is a front elevation of the same 105 mechanism, portions being broken away;

Fig. 3 is a front elevation of the middle parts of the apparatus;

Fig. 4 is a horizontal section on the line, 4—4, of Figs. 3 and 5;

Fig. 5 is an upright section on the line, 5—5, of Fig. 4;

Fig. 6 is an upright section on the line, 6—6, of Fig. 4;

Fig. 7 is a front elevation illustrating the above-mentioned second form;

Fig. 8 is an upright section through the 10 two right hand conveyer sections shown in Fig. 7;

Fig. 9 is a horizontal section on the line, 9—9, of Fig. 7, portions being broken away;

Fig. 10 is a horizontal section through the 15 right hand conveyer section shown in Fig. 7, portions being broken away.

Referring first to Figs. 1 to 6, inclusive, of said drawings, A is the stationary body of the machine. A¹ is the sewing head. For 20 details concerning said head and the means for operating it, reference is made to my above-mentioned Letters Patent.

In the front part of the body of the machine are two upright counterweight guides, 25 A². Between said guides is a counterweight, A³, engaging said guides for confining said weight to up-and-down movement. On the body of the machine is a housing, A⁶, in which are two guide rollers, A⁵. A cable, A⁴, 30 extends from the counterweight upward and over said guide rollers and then down over the left hand face of the machine to a lever A⁷, to which it is coupled. Said lever is parallel to said face of the machine, and its 35 rear end has a longitudinal slot, A⁸, which receives a horizontal wrist, A⁹, located on the body, A. By this means, the rear end of said lever is held against up-and-down movement but is allowed to move endwise 40 to the extent of the length of said slot. The forward end of said lever extends beneath the main conveyer section, B, and is coupled to the latter at A¹⁰, so that the position of said end of the lever 45 is determined by the position of that part of the main conveyer section. The position of the lever, A⁷, determines the position of the counterweight; the latter constantly drawing on the cable, 50 A⁴, and tending to lift the forward end of said lever. In other words, the counterweight is put into such operative relation with the main conveyer section as to constantly tend to lift said section.

55 One end of the main conveyer section, the end to which the lever, A⁷, is coupled, is the discharge end and extends beneath the sewing head, A¹. The opposite end, the receiving end, of said main section extends approximately horizontally to a point distant from said sewing head and is hinged at B¹, on an axis which is horizontal and transverse to the length 60 of said section. This construction provides for the bodily turning of said

section on said axis through a short arc, whereby the discharge end of said section, the end which is under the sewing head, may be moved upward and downward to bring the upper ends of bags moving on 70 said section to the sewing head. Within said main section, opposite the body, A, is a horizontal cross shaft, B², to which is coupled the upper end of a link, B³. The lower end of said link is coupled to a crank, B⁴, 75 which is rigid on a transmission shaft, B⁵, which is horizontal and perpendicular to the front of the machine and is actuated by means disclosed by my above-mentioned Letters Patent. By turning said crank into different positions, the elevation of the link, B³, is varied, and thereby the elevation of the discharge end of the main conveyer section is varied accordingly. When the crank is in its lowest position, that end of the conveyer section is in its lowest position, and when said crank is turned into its highest position, that end of the conveyer section is in its highest position.

C is the stationary conveyer section. This 90 is in alinement with the main conveyer section and meets the hinged end of the latter. At its outer end, the section, C, has an idle transverse horizontal roller, C¹. The discharge end of the main conveyer section has 95 a transverse horizontal roller, B⁶, mounted on a shaft, B⁷, which rests in bearings, B⁸. The stationary section, C, has an upper floor, C², and the main section has a similar floor, B⁹. An endless belt, B¹⁰, rests upon 100 the floors, B⁹ and C², and extends over rollers, B⁶ and C¹.

On the rear end of said shaft, B⁷, is a sprocket wheel, B¹¹, to which is applied a drive chain, B¹², which is driven by means 105 associated with the body, A, of the machine, as described in my above-mentioned Letters Patent.

Said transmission shaft is turned in the proper direction to draw the upper part of 110 the belt, B¹⁰, from the roller, C¹, toward the roller, B⁶. Filled bags are set in upright position upon said belt, and the latter carries said bags to the discharge end of the main conveyer section. As the bags approach the sewing head, the attendant at the sewing machine actuates the controlling mechanism of the machine whereby the crank, B⁴, is positioned to bring the upper ends of the bags to the height of the stitching line—the horizontal line in which the sewing head forms the stitches.

Between and parallel to the shafts, B² and B⁷, is an idle shaft, B¹⁴, on which is a deflecting roller, B¹³, over which the belt, B¹⁰, 125 extends for deflection to avoid contact with the shaft, B², and the upper end of the link, B³.

D is the auxiliary conveyer section. This is located at the left of and in approximate 130

alinement with and meeting the end of the main conveyer section. On the receiving end of the section, D, the end which meets the section, B, are a pair of hook-form arms, 5 D¹, one of which rests on one bearing, B⁸, and the other on the other bearing, B⁹, of the main section. By this means, that end of the auxiliary section is coupled or hinged to the main section to be supported and carried up and down thereby. For a purpose 10 to be hereinafter explained, the upper face of the receiving end of the auxiliary section is made a little lower than the adjacent upper face of the main section. In the opposite 15 or discharge end of the auxiliary section is a horizontal, transverse shaft, D², having ends projecting beyond the sides of said section. To said ends of said shaft is coupled the upper end of a rocking support, D³. 20 The lower end of said rocking support is coupled to a fixed support, D⁴. In its up-and-down movements, the receiving end of the auxiliary section must follow the arc traversed by the bearings, B⁸. This involves 25 a bodily endwise movement of the auxiliary section. The rocking support, D³, permits such endwise movement. On the shaft, D², are a pair of rollers, D⁵. At the opposite end of said section is a horizontal, transverse shaft, D⁶, on which are a pair of rollers, D⁷. Between the rollers, D⁵, is a sprocket wheel, D⁸, and between the rollers, D⁷, is a sprocket wheel, D¹⁰, rigid on the shaft, D⁶. An endless sprocket chain, D¹¹, 30 extends around the sprocket wheels, D⁸ and D¹⁰, and has ears, D¹². An endless belt, D⁹, surrounds the rollers, D⁵ and D⁷, and the sprocket wheels, D⁸ and D¹⁰, and the ears, D¹², are secured to the inner face of the belt. 35 At each side of the upper part of the sprocket chain, D¹¹, is a floor, D¹⁶, which serves as a support for the belt, D⁹. The front end of the shaft, D⁶, projects forward beyond the bearing, B⁸, and rigid on said 40 end is a sprocket wheel, D¹³. The shaft, B⁷, projects forward through the forward bearing, B⁸. Rigid on said end is a sprocket wheel, D¹⁴. A sprocket chain, D¹⁵, extends around the sprocket wheels, D¹³, and D¹⁴, for 45 the transmission of power from the shaft, B⁷, to the shaft, D⁶. Thus the belt, D⁹, is driven through the rotation of the sprocket wheel, B¹¹. In other words, the belt supporting means of the auxiliary section is 50 actuated through power transmission from the belt supporting means of the main section. The sprocket chain, D¹¹, is used to avoid slack in the upper portion of the belt, D⁹. By this means, it is made unnecessary 55 to extend the driving sprocket chain, D¹⁵, to the shaft, D², at the discharge end of the auxiliary section, D. At each side of the receiving end of the auxiliary section is an inclined guide wall, D¹⁷. When a bag 60 reaches the extreme left hand or discharge

end of the main conveyer section, the support of said bag (the belt, B¹⁰) becomes inclined on the roller, B⁶. That causes the tilting and falling of the bag toward the auxiliary section, and usually directly upon 70 said section. If the bag falls sidewise, it meets the guide wall, D¹⁷, at that side and is deflected by said guide wall until the bag lies lengthwise on the belt, D⁹. If it is desired to have the bags remain standing 75 until the outer end of the auxiliary conveyer section is reached, the meeting ends of the two sections are brought to the same height. Then the bags, unless their bases are too small, will remain standing while passing 80 from one belt to the other.

At the outer or discharge end of the auxiliary conveyer section, the bags may be allowed to fall to any desired support or they may be removed from said section by attendants. 85

Referring now to Figs. 7, 8, 9 and 10, the body of the machine is in the form already described. In front of the machine body is a main conveyer section, E, which 90 is movable up and down bodily with a parallel movement. The transmission shaft, B⁵, is present as before. On said shaft is a cam, E¹, which supports the section, E. At the left of the shaft, B⁵, and parallel thereto 95 and at the same height is a shaft, E², extending through a bearing in the body, A. On the front end of said shaft, is a cam, E³, corresponding to the cam, E¹, and also supporting the main conveyer section, E. 100 Within the body of the machine, the shaft, B⁵, is surrounded by a sprocket wheel, E⁴, and the shaft, E², is surrounded by a corresponding sprocket wheel, E⁶, and a sprocket chain, E⁵, surrounds said sprocket wheels, so 105 that when the shaft, B⁵, is rotated, the shaft, E², is also rotated. Thus the cams, E¹ and E³, will be rotated in unison for raising and lowering said main section.

At the left or discharge end of the main 110 conveyer section is applied the discharge auxiliary section, D, in the manner already described in connection with Figs. 1 to 6, inclusive. At the right hand or receiving end of the main section is a receiving auxiliary conveyer section, F, hinged to the end of the section, E, by means of a shaft, F¹. 115

At its right hand or receiving end, the conveyer section, F, has a shaft, F², extending transversely and horizontally through 120 the section, and to the projecting ends of said shaft is applied a fixed support, F³. Within the section, F, an idle roller, F⁴, surrounds the shaft, F².

The section, E, has a floor, E⁷, and the section, F, has a floor, F⁵. 125

An endless belt, E⁸, extends over the two sections, E and F, and around the rollers of said sections.

The filled bags are placed on the auxiliary 130

receiving section, F, and are carried by the belt, E^a, to the section, D, the delivery of the bags to the latter section being the same as already described concerning the delivery 5 of bags from the section, B.

The left-hand end of the section, F, varies a little from upright movement, and it correspondingly moves the section, E, end-10 wise. The section, D, adapts itself to the up-and-down and endwise movements of the section, E.

I claim as my invention,

1. In an apparatus of the nature described, the combination with the sewing head, of a main conveyer section and an auxiliary conveyer section, said sections being placed end to end and the main section being located under the sewing head and movable up and down, and the end of the 15 auxiliary section which is adjacent the main conveyer section being movable up and down relatively to its other end, substantially as described.

2. In an apparatus of the nature described, the combination with a sewing head, of a main conveyer section and an auxiliary conveyer section, said sections being placed end to end and the main section being located under the sewing head and movable 20 up and down, and the end of the auxiliary section which is adjacent the main conveyer section being coupled to the main section for movement up and down relatively to its other end, substantially as described.

3. In an apparatus of the nature described, the combination with the sewing head, of a main conveyer section and an auxiliary conveyer section, said sections being placed end to end and the main section 30 being located under the sewing head and movable up and down, and the end of the auxiliary section which is adjacent the main conveyer section being movable up and down while the opposite end of the auxiliary section is held at approximately unchanged 40 level, substantially as described.

4. In an apparatus of the nature described, the combination with the sewing head, of a main conveyer section and an auxiliary conveyer section, said section being placed end to end and the main section being located under the sewing head and movable up and down, and the end of the auxiliary section which is adjacent the main 50 conveyer section being movable up and down synchronously with the main section while the opposite end of the auxiliary section is movable endwise, substantially as described.

5. In an apparatus of the nature described, the combination with the sewing head, of a main conveyer section and an auxiliary conveyer section, said sections being placed end-to-end and the end of the main section adjacent the auxiliary section

being located under the sewing head and 65 movable up and down, and the opposite end of the main section being distant from the sewing head and hinged to a relatively fixed support, and the end of the auxiliary section which is adjacent the main conveyer 70 section being movable up and down synchronously with the adjacent end of the main section, substantially as described.

6. In an apparatus of the nature described, the combination with the sewing 75 head, of a main conveyer section and an auxiliary conveyer section, said sections being placed end-to-end and the meeting ends of said sections being coupled to each other and together movable up and down, and their opposite ends being held at approximately unchanged levels, substantially as described.

7. In an apparatus of the nature described, the combination with the sewing 85 head, of a main conveyer section and an auxiliary conveyer section, said sections being placed end-to-end and the main section being located under the sewing head and movable up and down, and the end of the auxiliary section which is adjacent the main conveyer section being movable up and down synchronously with the main section and relatively to its other end and each of said sections comprising a conveyer belt, and 95 means for driving said belts, substantially as described.

8. In an apparatus of the nature described, the combination with a sewing head, of a main conveyer section and an auxiliary 100 conveyer section, said sections being placed end-to-end and the main section being located under the sewing head and movable up and down and the adjacent end of the auxiliary section being movable up and down 105 synchronously with the main section and relatively to its other end and each of said sections comprising a conveyer belt and rotatable belt supporting means, means for driving the belt supporting means of one 110 of said sections, and means for transmitting motion from said supporting means to the supporting means of the other conveyer section for driving the belt of that section, substantially as described.

9. In an apparatus of the nature described, the combination with the sewing head, of a main conveyer section and a discharge auxiliary conveyer section, said sections being placed end-to-end and the main section being located under the sewing head and movable up and down, and the end of the auxiliary section which is adjacent the main conveyer section being movable up and down synchronously with the main section 120 and relatively to its other end, and each of said sections comprising a conveyer belt, the flat upper faces of said belt being separated 125

at the meeting ends of said sections in order that a filled bag arriving at the end of the main conveyer section will lose support and fall lengthwise upon the auxiliary section, substantially as described.

- 5 10. In an apparatus of the nature described, the combination with a sewing head, of a main conveyer section and a discharge auxiliary conveyer section, said sections being placed end-to-end and the main section being located under the sewing head and movable up and down, and the end of the auxiliary section which is adjacent the main conveyer section being movable up and down 15 synchronously with the adjacent end of the main section and relatively to its other end, and being lower than said end of the main section, in order that a filled bag arriving at the end of the main conveyer section will 20 lose support and fall forward lengthwise

upon the auxiliary section, substantially as described.

11. In an apparatus of the nature described, the combination with the sewing head, of a conveyer section located under 25 the sewing head and movable up and down, a counter-weight located within the body of the machine, cable guiding means located above the counter-weight, a lever having one end coupled to said conveyer and having its 30 other end coupled to the body of the machine, and a cable extending from said counter-weight upward over said supporting means and downward to and forming connection with said lever, substantially as 35 described.

In testimony whereof I have signed my name this 2nd day of March, in the year one thousand nine hundred and eighteen.

JESSE E. MILLER.
